W. H. Campfield,
ATTORNEY.

UNITED STATES PATENT OFFICE.

FRANK DREYER, OF ELIZABETH, NEW JERSEY.

DEVICE FOR TURNING POCKET-LIKE ARTICLES.

1,355,947.

Specification of Letters Patent.

Patented Oct. 19, 1920.

Application filed August 26, 1919. Serial No. 319,976.

To all whom it may concern:

Be it known that I, FRANK DREYER, a citizen of the United States, and a resident of Elizabeth, county of Union, and State of

5 New Jersey, have invented certain new and useful Improvements in Devices for Turning Pocket-Like Articles, of which the following is a specification.

This invention relates to an improved machine for turning pocket-like articles, and particularly articles of apparel, such as soft turn-down collars, although it can be utilized for turning other articles, particularly when such articles require the initial 15 turning at the corners.

An instance of the use of this device is in the turning of collars, particularly of the turn-down style when made of soft fabric and which, when manufactured, are made 20 inside out; that is, the lining and the inner lining are placed outside of the fabric of which the garment is made and then stitched, and after this is done the collar must be turned so that the fabric is turned 25 to the outside.

In collars of this type the styles sometimes require a rather long point, and in turning these by hand the operators take up a great deal of time and sometimes use a tapered stick or similar implement to turn the 30 corners, and in working rapidly the use of this implement sometimes tears or rips the article.

In my improved device the corner of the 35 article is placed on a finger, and a coöperating finger is placed end to end with the first finger, the fingers being so constructed that the extreme point seated on the first mentioned finger is turned first and then the 40 article itself is turned. In this way the extremity or the point of the pocket-like article undergoes the initial step of the operation, is not subjected to any tearing or ripping strain and is held in this position 45 until the turning of the entire corner of the article is completed.

The invention is illustrated in the accompanying drawing, in which one form of machine embodying my invention is illustrated, 50 and in which drawing Figure 1 is a side view of such machine and Fig. 2 is an enlarged view of the ends of the fingers, the upper finger being shown in section.

The machine consists of two fingers that 55 are adapted to meet end to end, and to provide for the meeting and separation of these

fingers they are movable relative to each other, the preferred way being to mount one of the fingers in fixed position and having the other finger movable.

In the drawing, 10 is the fixed finger fastened to a suitable support 11 which rests on the bracket 12, the movable finger 13 being slidable in bearings 14 on the bracket 12, and while the details of the machine for causing the meeting and separation of the fingers are not essential, I have illustrated one type in which the bracket 12 is mounted on a suitable stand or table 15. The bracket 12 has means for pivotally supporting the lever 16, which is connected by a rod 17 with the foot lever 18, so that when the foot is pressed forward the movable finger is moved upward, and when the foot is tilted the other way, that is, the outer end of the foot lever is depressed, the movable finger is moved downward or away from the fixed finger.

The support 11 is preferably bent or doubled upon itself in a big enough arc to make the necessary clearance between the finger 10 and the support 11. The fingers 10 and 13 are tapered toward their ends, at least one of the fingers, in this form the finger 10, having a pin 19 projecting therefrom, which pin forms the tip of the finger and can retreat longitudinally because it can slide in the finger, the finger being recessed to contain the spring 20 which bears on the end or head 21 of the pin.

To permit the easy installation of the pin and the spring I may secure the pin to the end of the support by means of a sleeve 22, which covers the end of the finger and the end of the support, the finger, when in place, insuring the abutment of the spring against the end of the support, and when removed permitting the easy removal of the spring and the pin from the finger.

A collar is shown in dotted outline as at 23 in Fig. 2, and when the corner of a collar or other pocket-like article is to be turned it is held by the operator up against the pin 19, the spring 20 being stiff enough to resist ordinary pressure incidental to placing the collar in position, and then the movable finger is moved up so that its pointed end is opposite the end of the pin 19, thus tightly holding the very tip of the corner, and a further pressure tightens this grip and also causes the pin to retreat, and the pin, in retreating, passes to the inner end of the re-

cessed or counter-sunk portion 24 in the end of the finger 10. The counter-sunk portion 24 and the end of the finger 13 now hold the tip of the corner in turned position; in 5 other words, the initial turning of the tip has been accomplished and instead of pointing downward, as in Fig. 2, the tip of the article 23 will be pointed in the reverse direction, that is, upward. All the operator 10 has to do now is to take the collar, and while holding these elements in the position just described, turn down the article over the finger 13 and the operation is finished.

To provide against straining the support 15 11 or causing unnecessary pressure of the movable finger against the fixed finger, I prefer to limit the movement of the movable finger by means of a collar 25 which, abutting against the bearing 14, stops the movable finger when it has reached a point in 20 the counter-sunk end of the finger 10 to firmly grasp the material of which the pocket-like article is made.

I claim:

1. A machine for turning pocket-like articles consisting of two fingers adapted to meet end to end, one of said fingers having its end countersunk, a pin projecting from the countersunk end to form a tip for the finger, and means for yieldingly holding the 30 tip in advanced position.

2. A machine for turning pocket-like articles consisting of two fingers adapted to meet end to end, one of said fingers having a pin slidable therein, and a spring in the 35 finger and bearing on the pin so that the pin normally projects to form a tip, the finger having the end from which the pin projects recessed so as to receive the end of the second finger when the fingers meet and 40 the tip retreats.

In testimony that I claim the foregoing, I have hereto set my hand, this 22nd day of August, 1919.

FRANK DREYER.
